FLUSH TYPE FIRE HYDRANT AND HIGHWAY CONSTRUCTION THEREFOR

Carlyle H. Scott, Forest Hills, and Paul H. Scott, Flushing, N. Y., assignors to Flush Hydrant Corp., Corona, N. Y., a corporation of New York

Application March 11, 1941, Serial No. 382,682

1 Claim. (Cl. 137—13)

This invention relates generally to fire hydrants, and more particularly to highway constructions therefor, and coordinately combines the features of providing hydrants which do not extend above the level of the sidewalk or highway and constructional features which make flush type hydrants available at such street or sidewalk levels.

Our invention is a continuation-in-part of our application Serial No. 288,924, filed August 8, 1939, now Patent 2,234,635, granted March 11, 1941, for Flush type fire hydrant.

Our invention, as in our prior application above identified, has for its aim to overcome the many disadvantages of the old style fire hydrant which projects above the sidewalk and thereby constitutes an obstruction which is a menace to pedestrians and which is liable to be damaged by automobiles and is, by reason thereof, frequently so damaged.

As set forth in our prior application, these old type fire hydrants, due to their obstructive nature, are located away from street corners and thereby in such locations valuable space is lost as safety measures initiated by Fire Department regulations prohibit obstructing space near a fire hydrant. Again, since snow is frequently allowed to accumulate at points between intersections where it has been found convenient to locate hydrants extending above the sidewalk level, these hydrants are thereby obscured and rendered inaccessible when urgently needed or, if passage thereto is provided, these locations limit the line and direction through which the hose may be extended. Furthermore, these old type hydrants which project above the sidewalk or highway level are difficult to service. Since they extend below street level, excavation is necessary to reach movable valve parts as these sections may require replacement occasioned by frost or wearing out of valve surfaces.

While it is known to us to provide hydrants or stand pipes below the street level, employing water control valves customarily used in hydrants located above the street level, these constructions have not solved the problems for making flush type fire hydrants available in view of the excessive space which such mechanism requires.

Accordingly, it is an object of our invention to provide, in a fire hydrant, a construction whereby it may have its operating control valves flush with the street sidewalk or highway level wherein it may be located at street intersections to render this mechanism readily accessible, free

from obstruction during all seasons of the year, and provide the maximum space surrounding this mechanism for the feed of fire hose, working space in relation thereto and working space in relation to servicing and maintenance of this mechanism economically and coordinately in a highway construction which will make possible the achievement of these objectives.

It is a further object of our invention to provide a highway construction wherein the location of flush type hydrants is made feasible so that obstruction is minimized, accessibility is facilitated, maximum space is provided for operation and for servicing, without loss or unusual alteration of existing highway constructions.

Further objects of our invention reside in providing a flush type hydrant construction which makes possible, mechanically as well as economically, the employment of these constructions at street intersections, independent of weather conditions and free from spacial disadvantages.

To attain these objects and such further objects as may appear herein or be hereinafter pointed out, we make reference to the accompanying drawings, forming a part hereof, in which—

Figure 1 is a plan view of a fragment of a street highway, showing the location of our invention;

Figure 2 is a fragmentary sectional view taken on the line 2—2 of Figure 1;

Figure 3 is a fragmentary magnified sectional view of the main control valve;

Figure 4 is a plan view of another embodiment of our invention;

Figure 5 is a fragmentary sectional view showing a still further embodiment of our invention.

Making reference to the drawings, we have shown a portion of the highway 10 adjacent a corner intersection or street corner 11, and at which point the curb line 12 follows the contour of the street intersections, thereby defining the sidewalk 13. This space, to each face of the building line, provides the maximum accessible space, in connection with which our invention is utilized in the preferred embodiment thereof, utilizing part of the invention divided from our prior aforementioned application.

At this intersectional point of the street, it has been found most convenient to locate the catch basin or cess pool 14, as it is the low point for surface drainage for large areas of highway.

So much of the features of our prior applica-

tion as involve the combination of a sidewalk portion adjacent the intersection of two streets, together with a flush type hydrant, is therefore divided from our prior application aforementioned, for reasons amplified in our prior filed application and which will become apparent as this description proceeds.

More specifically, in relation to the highway construction exemplified in Figure 1, which is the preferred embodiment of our present invention, adjacent the cess pool or catch basin 14, defined by the masonry walls 15 and 16 and which is provided with the opening 17 and a manhole cover 18, we provide a sump 19, the floor 20 of which extends over the wall 15 and terminates into a drainage orifice 21 formed in the wall 15. The sump 19 has its opening 22 provided with a cover flange 23 and a cover 24, serving as a closure for the sump 19.

Through the bottom wall 20 there is extended a barrel 25, the lower end of which, 26, is connected to a T 27, which by the bell or flange 28 is in turn connected to the water main 29. The connection with the end of the barrel may be effected by screw threading or a weld joint 30.

The upper end of the barrel 25 is provided with a bonnet 31 which, in turn, carries a plurality of outlet sections 32, provided with control valves 33. Hose connectors 34 are provided at the terminals of the sections 32 controlled by the control valves 33, as described.

While the bonnet 31 may be welded to the barrel 25 along the weld line 35, in the embodiment illustrated, using the valves from the main, which will hereinafter be described, this bonnet may be attached to the barrel 25 by bolt connected flanges 35a, more particularly exemplified in Figure 5 and in our prior application above mentioned. A bonnet connected to the barrel by bolt connection is particularly adapted for valve servicing of the construction shown in Figure 5 and in our prior filed application.

Referring again to Figures 1, 2 and 3, we provide the T 27 with an enlarged flange 36, anchored in the wall 15 of the catch basin. The T 27 has a neck 37 adjacent the flange 36. Into this neck is threaded a spider 38 formed with a valve seat 39 and a guide or bearing 40 axially located by the fins 41, defining a passage 42. A stem or rod 43 extends through the guide or bearing 40 and has its end 44 provided with a valve head 45, adapted to seat upon the valve seat 39 previously described. The T 27, adjacent the right hand side when viewing Figure 3, is formed with a screw threaded neck 46, into which is screw threaded the cap 47, which has on its inner face 48 a bearing 49, through which the stem 43 passes. The bearing 49 is axially suspended by the fins 50, providing a passage about the fins and which passage terminates in the orifice 51 formed in the cap 47.

The enlarged flange 36 has an offset 52 adjacent one side thereof, in which offset there is positioned an arm 53 provided with bearings 54 for a rock shaft 55. On this rock shaft there is mounted a bell crank lever 56. The upper arm 57 of the bell crank lever is provided with a slotted bearing 58 and is positioned between the fingers 59 of the knuckle joint 60. A pin 61 connects the knuckle joint and arm 57 of the bell crank lever 56. The knuckle joint 60 is screw threaded to the end 62 of the shaft 43.

Referring again to the bell crank lever 56, it has its second branch 63 provided with a connector bearing 64, which is common to it and 75

the rod 65. The rod 65 extends within the catch basin along the wall 15, upwardly through the drain 21, to operating mechanism for giving it reciprocable movement. Various linkage arrangements may be employed to provide the rod 65 with reciprocable movement. However, we exemplify and prefer that reciprocable movement be imparted to the rod 65 by connecting the same adjacent its end 66 to a link 67. This link, in turn, is pivotally connected to the elbow 68, formed on the cover 24. The cover is pivotally mounted on the pivot center 69.

With the construction as described, it will be observed that upon pivotal movement of the cover plate 24, to open the same, an upward pull will be imparted to the rod 65, thereby actuating the bell crank lever 56 and, in turn, projecting the stem or rod 43 and unseating the valve head 45. As the movement of the rod 43 progresses, the end 62 thereof is moved in the direction of the cap 47. The cap 47, at its orifice 51, is provided with a seat 70. On the stem 43 there is provided a valve head 71 adapted to seat upon the valve seat 70. Upon movement of the rod 65 by the cover 24 or other operating mechanism substantially completely to unseat the valve head 45 from its valve seat 39, the valve head 71 will be seated upon the valve seat 70 and thereby close the orifice 51.

At this point it will be observed that the T being connected to the water main 29, the water supply will be furnished to the barrel 25, and during the interval of time for completely opening the passage 42 by unseating the valve head 45, the orifice 51 will likewise be open, permitting a discharge of water through the orifice 51, through the flange 36, into the catch basin or cess pool 14. This preliminary discharge will serve to scavenge rust or detritus from the barrel 25 and which may have accumulated within the T 27, into the catch basin 14.

It will be observed that the drain orifice 51 is small compared with the orifice 42, thereby minimizing the amount of pressure necessary to retain the valve head 71 upon the seat 70.

For convenience, the valve head 45 and its assembly will be referred to as the "barrel valve" and the valve head 71 and its assembly will be referred to as "by-pass valve."

It will be readily understood that upon reverse operation, the rod 65 will be moved downwardly by its operator—in the exemplified form, the cover 24—seating the barrel valve to its closed position and unseating the by-pass valve. This operation will serve to open the by-pass valve and drain the barrel 25 of any accumulated water through the flange 36, into the catch basin 14, to the bottom thereof (not shown). It will be observed that the T 27 is disposed to be extended well below the frost line but above the catch basin orifice 72, which is connected to the sewage line 73.

Referring now to the control valves 33 housed within the sump 19, it will be observed that when the cover 24 is open, hose lines may be extended along each direction of the intersectional streets and will afford space at the intersection of maximum degree for the operators. Where located at an intersection, most usually kept clear during snow or sleet, maximum accessibility will be afforded. Close proximity of location of fire equipment is also thereby facilitated, minimizing the obstruction of the highway in either direction.

Where the hydrant is located as shown, with

the valve assembly terminating into the catch basin 14, servicing of this mechanism is facilitated through the opening 17 of the catch basin merely by removal of the manhole cover 18. Thus, merely by cutting off the valve controlling the water main, a workman may reach the opening 36 through the catch basin and upon disconnecting the rod 65, may fully service the main valve or by-pass valve, replacing these parts as conditions may require. Excavation to reach the movable parts is thereby avoided.

It will also be observed that by directing the bottom 20 of the sump 19 to terminate adjacent the drain 21 leading to the catch basin 14, the sump is kept clear of water, overflowing during the use of the hydrant.

Furthermore, it will be observed that since the control mechanism for the main valve and by-pass valve is entirely below the level of the street and is accessible from the catch basin, replacement of the control valves 33 and servicing of these parts may be done independent of the opening of the main valve.

It will also be observed that since the cess pool or catch basin is primarily an existent construction, installation of our contrivance may be accomplished with the minimum amount of excavation, requiring merely entrance through the wall 15 for installation of the device.

While we have referred to an intersectional installation wherein the catch basin or cess pool is in contiguous position with the manhole positioned within the curb line 12 for access to the by-pass valve, it will be understood that where the cess pool or catch basin is made accessible through a street manhole, we contemplate positioning our flush type hydrant in close relationship to the street manhole cover. Such construction is generally illustrated in Figure 4 wherein the flush hydrant sump 19a is shown adjacent to the street overflow drain 20a. This, in turn is covered by a street manhole cover 21a in the same general relationship as that contemplated in connection with the embodiment illustrated in Figures 1 and 2, the axial line of the barrel and cess pool or catch basin drain being at right angles to the curb 12a. In all other respects, the assembly may be in the form illustrated and described in connection with the embodiments of Figures 1, 2 and 3.

In Figure 5 we have shown an embodiment closely related to our prior application aforementioned, which will issue as Patent No. 2,234,635, wherein provision is made for servicing the flush hydrant main valve and the by-pass valve mechanism by reason of the novel assembly of the flush hydrant and catch basin or cess pool contiguously.

In this embodiment, a sump 74 is defined by the box 75, made of masonry, concrete or sheet metal. Through the bottom 76 there is extended the barrel 77. The lower end of the barrel 77 is connected by the flange 78 to the water main 79. The upper end is provided with a bonnet 80, carrying the control valves 81 and connected to the barrel 77 by the bolt fastened flange 35, previously mentioned.

Adjacent the upper end of the barrel, we provide a rock shaft 82 for pivotal mounting. This mounting is water tight and has an arm 83, fixedly mounted on said rock shaft. On this rock shaft is provided a second arm 84, to which is extended a link 85, a coupler 86, terminating in the knuckle 87, connected with the bracket 75

88, rigidly mounted upon the cover 89, pivoted on the pin 90, having a bearing in the frame 82'.

The free end 85 of the arm 84 extends through a drain orifice 86 leading to the cess pool or catch basin 14. The free end 85 has a lost motion coupling to the rod 91, thereby securing limited slideable movement between the stop 92, when pulling action is desired upon the rod 91, or the stop 93 when pushing action is desired against the rod 91.

The lower end of the rod is connected to the branch 94 of the bell crank lever 95, pivoted on the bearing 96 mounted upon the by-pass sleeve 97. The second branch 98 of the bell crank lever 95 is connected to the rod 99, passing through the bearing 100 formed in the spider 101. The spider is screw threaded in the neck 102, which terminates into the barrel 77. The spider 101 provides a by-pass orifice 103, and a valve seat 104, which seat is closed by the valve head 105, mounted upon the rod 99.

Connected with the arm 83 is a connecting rod 106, passing through the barrel 77 and connected by the knuckle joint 107 to the stem 108. The stem 108, through the bearing of a spider 109, is provided with a valve seat 110 adapted to be closed by the main valve head 111. It will be observed that the spider 109, with its valve seat and valve head assembly, may be screw threaded into the neck 112 adjacent the lower end of the barrel 77, immediately below the opening of the by-pass sleeve 97.

The actuation of the device just described will be readily understood to follow, in certain aspects, the details of our prior filed application in that opening the cover 89 will serve to open the main valve 111 through the intermediate linkage provided by the rock shaft 82, the arm 83 and the connecting rod 106, as the arm 84 is upwardly lifted by the connection made between the arm 84 and the bracket 88 through the medium of the link 85.

After the main valve begins to open, the end 85 engages the stop 92, thereby to draw upwardly the rod 91, which through the medium of the bell crank lever 95, pulls the by-pass valve 105 to its closed position. Conversely, upon closure of the cover 89 to close the main valve, the by-pass valve will first open, and a predetermined time thereafter, the barrel valve will close. This operation, with the mechanism as shown in Figure 5, and the opening of the cover, will first permit water to reach the barrel 77 and with the control valves 81 in the closed position, it will serve to scavenge any detritus, such as rust, in the barrel, discharging it through the by-pass valve until the by-pass valve is completely closed.

In the reverse operation, the main valve 111 will first close, and the by-pass valve 105 will then open, permitting any accumulated water in the barrel 77 to drain through the by-pass valve into the cess pool 14.

As in the prior embodiment, ready access to the valve mechanism is obtainable through the cess pool 14. The contiguous arrangement of the cess pool 14 and the flush type hydrant not only provides for ready drainage of the barrel 77 but also of the sump 74, in addition to other features heretofore stressed in connection with the prior embodiment.

It will thus be observed that we have provided a novel combination of flush hydrant and highway construction, having the features of accessibility, serviceability, facility of replacement and economy of construction.

It will be understood that while our invention, in its preferred form, may utilize all of the co-ordinated parts, our invention is not to be limited to the entire assembly but that separate parts thereof have independent utility, all as outlined herein and more specifically defined in the appended claim.

Having thus described our invention and illustrated its use, what we claim as new and desire to secure by Letters Patent is:

In a hydrant, the barrel of which is arranged to extend through a sump below the frost line,

with the controls thereof within the sump and enclosed by a cover flush with the sidewalk level, the combination with the barrel of said hydrant of a coupling, one end whereof interfits with the barrel, a passage for connection with the water main and a passage serving as a by-pass, arranged to discharge water from said barrel to a catch basin, said coupling including a barrel valve assembly and a by-pass valve assembly accessible through the by-pass.

CARLYLE H. SCOTT.
PAUL H. SCOTT.
